[57] CLAIM

The ornamental design for protective shoe for dogs, as shown.

DESCRIPTION

FIG. 1 is a right side elevational view of a protective shoe for dogs showing my new design, as embodied in a shoe for the front feet.

FIG. 2 is a front elevational view thereof.

FIG. 3 is a left side elevational view thereof.

FIG. 4 is a rear elevational view thereof.

FIG. 5 is a top plan view thereof.

FIG. 6 is a bottom plan view thereof.

FIG. 7 is a right side elevational view of a modified form of the protective shoe for dogs shown in FIG. 1, as embodied in a shoe for the rear feet.

FIG. 8 is a front elevational view of FIG. 7.

FIG. 9 is a left side elevational view of FIG. 7.

FIG. 10 is a rear elevational view of FIG. 7.

FIG. 11 is a top plan view of FIG. 7.

FIG. 12 is a bottom plan view of FIG. 7.
